UNITED STATES PATENT OFFICE.

ERNEST B. FAHNESTOCK, OF PLANDOME, NEW YORK; EDITH MARY JORDAN AND FRANCES HODGSON BURNETT, BOTH OF PLANDOME, NEW YORK, EXECUTORS OF SAID ERNEST B. FAHNESTOCK, DECEASED.

ATOMIZER AND METHOD OF ATOMIZING.

Application filed September 26, 1917. Serial No. 193,335.

To all whom it may concern:

Be it known that I, ERNEST B. FAHNESTOCK, a citizen of the United States of America, and a resident of Plandome, Nassau County, and State of New York, have invented certain new and useful Improvements in Atomizers and Methods of Atomizing, of which the following is a specification, reference being had to the accompanying drawings, forming a part thereof.

My invention relates to atomizers and methods of atomizing liquids and its object is to provide a simple and efficient device for this purpose and furthermore to provide a new method of atomizing.

Another object is to provide a device and a method for breaking a liquid into an exceedingly fine spray, mist or vapor.

I have discovered that when a porous body or a body having capillary characteristics, holds a liquid such as gasoline or kerosene, if another member such as a piece of perforated sheet metal, is rubbed against such a body, the liquid comes off from the body in most minutely divided particles. I have also discovered that a liquid may be thrown off from a resilient element in the form of a fine mist or vapor by sudden springing of such an element. I propose to use these principles for the construction of atomizers and for providing my new and useful methods of atomizing.

In order that this invention may be understood I will now describe the same in the following specification, and then point out the novel features thereof in appended claims.

Referring to the drawings:

Figure 1 is a front elevation of a simple form of atomizer which embodies my invention.

Figure 2 is a side elevation partly in section, of the same device.

Figure 3 is a front elevation of a modified form of disc,—one of the parts shown in the preceding figures.

Figure 4 is a sectional side elevation of a part of an atomizer of somewhat different construction, which also embodies my invention.

Figure 5 is a rear elevation of the cover plate of the apparatus shown in Figure 4.

Figure 6 is a sectional plan view of a part

of the cover plate of Figure 5, drawn on a larger scale to more clearly show its construction. The section of this figure is taken on the line 6—6 of Figure 5.

Figure 7 is a view corresponding to Figure 6, showing a modified form of construction.

Figure 8 is a sectional side elevation of a still further modified form of construction which is also an embodiment of this invention.

Figure 9 is a front elevation of the rotating plate of the atomizer shown in Figure 8.

Figure 10 is a sectional side elevation of an atomizer which embodies my invention, constructed and arranged still differently.

Figure 11 is a sectional front elevation of the apparatus shown in Figure 10, the section being taken on the line 11—11 of the latter figure.

Like characters of reference designate corresponding parts in all the figures.

Referring first to Figures 1 and 2,—designates a base upon which the other parts of the device are mounted. 11 is a stationary casing affixed to the base as at 12, and having a cylindrical bore 13. 14 is a disc of perforated sheet metal, held over the front end of the casing 11 by a ring 15 threaded onto the casing. At the other end of the casing is a screw-threaded boss 16 in axial alignment with the bore 13 in which is supported an adjusting member 17. This forms a bearing for a shaft 20.

The shaft 20 holds at its forward end a plate 21 to which is affixed a circular pad 22 of porous material such as wool felt. 23 is a spring which bears against the plate 21 and against a washer 24 at the end of the adjusting member 17. This spring forces the pad 22 against the disc 14. The other end of the shaft 20 is connected with the shaft of a motor 25 by a coupling 26.

27 is a liquid supply pipe. 28 is a regulating valve therein, and 29 a sight-feed below the valve.

Before specifically describing the devices shown in the other figures of the drawings, I will describe the operation of this apparatus. The liquid to be atomized is led to the pad 22 through the pipe 27. Relative movement between the pad 22 and the disc 14 is imparted by the rotation of the motor 25.

This rotates the pad which as has been shown, has one of its surfaces pressed against the disc. This operation results in the formation of a mist or spray of most minutely divided particles of the liquid which pass out through the perforations in the disc. The action may be varied by adjusting the valve 29, adjusting the spring pressure by turning the adjusting member 17, or by 10 varying the rate of rotation of the motor by a rheostat 25^A.

The disc 14^A shown in Figure 3 is like that shown in Figure 2, except that it is provided with radially disposed slots 18 instead of circular perforations. Its function is similar to that shown in the preceding figures. It is only necessary that the members be perforated or provided with apertures of some shape, and it is obvious 20 that a woven wire screen can be used if desired.

In the device shown in Figures 4, 5 and 6 there is a cover plate 30 over the front end of the casing 11 which closes this end of 25 the casing except at the center where an outlet 31 is provided. The inner surface of this cover plate is constructed with radially disposed grooves 32 which connect with and run outwardly from the outlet opening 31.

In this case the pad 22 is pressed against the inner surface of the cover plate and rotated over it. The spray or mist produced passes out through the orifice 31.

35 Instead of grooves, the inner surface of the cover plate may be constructed with inwardly projecting ribs 33 as shown in Figure 7, in which the cover plate is designated by 30^A.

40 It is not necessary to impart motion to the pad and in Figures 8 and 9, an atomizer is shown in which the pad is stationary. In this structure the pad is designated by 22^A. 40 is a stationary casing in which the 45 pad is supported. Its lower part forms a reservoir 41 into which the pad extends and which may be filled through an opening 42. 43 is an outlet for the atomized spray. The rear end of the casing is closed 50 by a cover plate 45 which has an internally threaded boss 45. 46 is an adjusting member which forms a bearing for a rotary shaft 47 and an abutment for a spring 48. On the inner end of the shaft is a rotary 55 plate 49 which is provided with radially disposed ribs 33^A like those shown in Figure 7 which are pressed against and moved over a surface of the pad 22^A.

In this case the capillary action of the 60 pad is depended upon to bring the liquid up to the surface over which the ribs are moved. This liquid is atomized by the rotation of the plate 49 and passes out in minutely divided particles through the discharge orifice 43.

In Figure 10, 50 is a cylindrical perforate shell held between brackets 51-52 which are affixed to the base 10 and held together by bolts 53. These brackets close the ends of the shell. A hollow shaft 54 is 70 rotatively supported in bearings in the brackets 51-52 and connected by a coupling 26 with a motor 25, the speed of which may be controlled by a rheostat 25^A.

On the shaft between the brackets is a 75 hub 55 to which wires or other fibres of a brush 56 are connected. These are of such length that the periphery of the brush is in contact with the inner surface of the shell 50.

The shaft 54 and hub 55 are provided with ducts 57 leading outwardly from the interior of the shaft. Other ducts 58 are provided through the shaft within its bearing in a bracket 52 within which a supply 85 chamber 59 is formed. The supply pipe 27 is connected with this chamber and as in the structure of Figure 2 has an adjusting valve 28 and a sight feed 29.

With this device the liquid is thrown 90 outwardly by centrifugal force and if rotated at high rates will atomize the liquid without the shell 50. The shell 50 when used acts as in the former structures to break up the liquid into minute particles 95 by the liquid carrying fibers rubbing over its perforated surface.

The arrangement shown in Figure 12 has a rigid pedestal 60 and a cap 61 bolted thereto between which is held the end of a flat inclined spring 62. The cap supports a cup 63 which has a valve 64 by means of which liquid may be dropped onto the spring which will run down its inclined surface and be distributed over it. 65 is a ratchet wheel the teeth of which engage the end of the spring. When this is rotated in the direction indicated by the arrow, the spring will be snapped from one tooth to the next and this will result in throwing off the liquid in finely divided particles.

The action of the devices shown may be regulated by adjusting the supply of liquid, the pressure between the relatively moving body and member, the rate of such relative movement, or by varying the effective area of the relatively moving parts. It is also possible to vary the minuteness of the particles of the spray by using members having apertures of different sizes.

I have illustrated and described several kinds of structures which embody my invention for the purpose of showing that it is not limited to any specific form of construction, and in fact intend no limitations other than those imposed by the appended claims.

What I claim is:

1. An atomizer comprising a liquid holding body and a member in contact therewith,

and means for atomizing said liquid by imparting relative rubbing movement between the body and the member.

2. An atomizer comprising a liquid holding body, a perforate member in contact therewith, means for supplying a liquid to the body, and means for imparting a relative rubbing movement between the body and the member.

10 3. An atomizer comprising an absorbent body, a perforate member in contact with a surface of said body, means for supplying a liquid to the body, and means for imparting relative rubbing movement between the body and the member.

4. An atomizer comprising a body having resilient fibres, a perforate member in contact with a surface of said body, means for supplying a liquid to the body, and means 20 for imparting relative rubbing movement between the body and the member.

5. An atomizer comprising a body of resilient fibres, a perforate member in contact with a surface of said body, adjustable means 25 for supplying a liquid to the body, and means for imparting relative movement between the body and the member.

6. An atomizer comprising a body of resilient fibres, a perforate member in contact 30 with a surface of said body, adjustable means for varying the pressure of said contact, means for supplying a liquid to the body, means for imparting relative movement between the body and the member, and 35 means for varying the rate of said movement.

7. An atomizer comprising a body of re-

silient fibres, a perforate member in contact with a surface of said body, adjustable means for varying the pressure of said contact, adjustable means for supplying a liquid to the body, means for imparting relative movement between the body and the member, and means for varying the rate of said movement.

40 8. The herein described method of atomizing which consists in holding a liquid in one body and atomizing said liquid by rubbing another member over a part of said body.

45 9. The herein described method of atomizing which consists of imparting relative motion between two bodies in constant contact, at least one of said bodies holding the liquid to be atomized.

50 10. The herein described method of atomizing consisting of holding a liquid in one body, pressing said body into contact with another body and rubbing one of said bodies with respect to the other.

55 11. The herein described method of atomizing which consists of holding a liquid in one member, maintaining another member in constant contact therewith and rubbing one of said members on the other.

60 12. An atomizer comprising a liquid holding body, a member in constant contact therewith and means for atomizing the liquid in said body by relative rubbing movement between said body and said member.

65 In witness whereof, I have hereunto set my hand this 25 day of September, 1917.

ERNEST B. FAHNESTOCK.
